UNITED STATES PATENT OFFICE.

WILLIAM W. MCCOY, OF CINCINNATI, OHIO.

ARCH-SUPPORTING SHOE.

1,335,172.

Specification of Letters Patent. Patented Mar. 30, 1920.

Application filed August 5, 1919. Serial No. 315,535.

To all whom it may concern:

Be it known that I, WILLIAM W. MCCOY, a citizen of the United States of America, and a resident of Cincinnati, in the county of 5 Hamilton and State of Ohio, have invented a new and useful Improvement in Arch-Supporting Shoes, of which the following is a specification.

It is customary to extend the heel of shoes 10 forward to a position beneath the scaphoid or the keystone bone of the foot, to give support to the feet of people who have fallen or weak arches.

Other means by which it has been attempted to afford relief to people thus afflicted are so called arch-supports which are to be placed within the shoe.

The objection to a shoe with an extension heel is that it is unsightly. The objection to 20 the arch-supports is that they exert a pressure upon the foot at all times even though the foot wearing the support be supporting no weight.

Another objection thereto is that they are 25 too stiff in movement.

The object of my invention is a shoe which has the appearance of an ordinary shoe, which will support the scaphoid bone without putting a tension on the muscles of the 30 foot and which will permit of easy movement of the foot.

These objects are attained by the means described in the specification and illustrated in the accompanying drawings in which:—

35 Figure 1, is a top plan view of a shoe embodying my invention.

Fig. 2, is a view partly in side elevation and partly in section of a shoe embodying 40 my invention.

The shoe has the usual heel α , outer sole α' and inner sole α'' . Between the inner and outer sole I mount a metal spring plate B. Plate B is made preferably of spring steel, is from two to two and one-half inches in 45 length, and has an approximately straight

side b . Its opposite side at the reduced end of the plate is approximately parallel to the side b but gradually diverges from the side b forming an expanded end b' . The edges of the plate are preferably curved slightly 50 upward.

The plate is secured either to the inner or to the outer sole by means of rivets, so that the straight edge b is parallel to the outer edge α' of the shoe and so that the expanded 55 end b' extends beyond the forward edge of the heel and in a position such that it will be beneath the scaphoid bone of the foot.

In use the spring exerts no pressure upon the foot except when a person is standing on 60 his feet. Thus it gives support to the arch and no discomfort to the person when he is resting. In taking a step, the spring permits the forward portion of the foot to have 65 its usual rotary motion.

Having thus described my invention, what I claim is:—

1. In a shoe the combination of a heel, an outer sole, an inner sole and a spring plate interposed between the inner and outer soles 70 and having its rear end supported by the heel and its forward end free, projecting beyond the heel and terminating at a point beneath that over which the scaphoid bone of the foot is located. 75

2. In a shoe the combination of a heel, an inner sole, an outer sole, and a spring support having one straight side and a curved side which at the forward end diverges from the straight side and forms an expanded 80 end upon the plate, the plate being located between the inner and outer soles and with its expanded end being free and extending beyond the heel and terminating at a position beneath the point over which the scaphoid bone of the foot is located. 85

In testimony whereof, I have hereunto subscribed my name this 4th day of August, 1919.

WILLIAM W. MCCOY.
